DESIGN FOR A STEP ATTACHMENT FOR
RUNG LADDERS

Karl A. Agricola, Saginaw, Mich., assignor to
Beauideal Inc., Saginaw, Mich., a corporation
of Michigan

Application April 19, 1948, Serial No. 145,806

Term of patent 14 years

(Cl. D15—8)

To all whom it may concern:

Be it known that I, Karl A. Agricola, a citizen of the United States, residing in Saginaw, in the county of Saginaw and State of Michigan, have invented a new, original, and ornamental Design for Step Attachment for Rung Ladders, of which the following is a specification, reference being had to the accompanying drawing, forming part thereof.

Fig. 1 is a side view in perspective of the step attachment for rung ladders, showing my new design;

Fig. 2 is a front perspective view of the step attachment shown in Fig. 1; and

Fig. 3 is a top plan view.

I claim:

The ornamental design for a step attachment for rung ladders, as shown.

KARL A. AGRICOLA.
